UNITED STATES PATENT OFFICE.

CHARLOTTE ELIZABETH HURD, OF UNADILLA, NEW YORK.

SHIRT-WAIST ATTACHMENT.

SPECIFICATION forming part of Letters Patent No. 633,845, dated September 26, 1899.

Application filed January 24, 1899. Serial No. 703,292. (No model.)

To all whom it may concern:

Be it known that I, CHARLOTTE ELIZABETH HURD, of Unadilla, in the county of Otsego and State of New York, have invented a new and Improved Shirt-Waist Attachment, of which the following is a full, clear, and exact description.

The object of my invention is to provide a simple, effective, and economic device especially adapted for attachment to dress and shirt waists for the purpose of enabling a skirt to be utilized for holding a waist in proper position or so that no space will be visible between a waist and skirt and whereby the waist will not work up in wearing.

A further object of the invention is to so construct the device that a pliable member will be a fixture upon the waist and may be passed through the wash as readily as the most pliable portion of the garment, the other member, which may be of spring material, being detachably supported in the pliable member.

Another object of the invention is to provide a waist attachment that will not be uncomfortable when worn and that will be concealed when the waist is upon the person and the attachment is connected with a skirt and whereby also ordinary hooks may be used upon the skirt for the purpose of connecting the skirt with the shirt-waist attachment.

The invention consists in the novel construction and combination of the several parts, as will be hereinafter fully set forth, and pointed out in the claim.

Reference is to be had to the accompanying drawings, forming a part of this specification, in which similar characters of reference indicate corresponding parts in all the figures.

Figure 1 is a rear view of a person wearing a waist to which the improved supporter is applied. Fig. 2 is a rear face view of the improved supporter and the portion of the material to which it is applied. Fig. 3 is a horizontal section taken practically on the line 3 3 of Fig. 2; and Fig. 4 is a longitudinal section taken through the supporter and a waist, taken practically on the line 4 4 of Fig. 2, and likewise a section through a portion of a skirt, said figure likewise illustrating the manner in which the skirt is sustained by the supporter.

The supporter A is attached to the central back portion of a waist B at or below the waist-line or between the waist-line and skirt-section of the waist, the supporter being horizontally applied. The supporter A is made in two sections—a body-section a and a supporting-section a'. The body-section a is attached permanently to the waist and consists of a strip or tape of fabric or other pliable or yielding material secured to the waist by lines of stitching or by any other well-known means, the said strip or tape being provided with a pocket 10 at each end formed upon its outer face, and the said tape or strip a of the body-section of the supporter is also preferably provided with a transverse loop 11 at or near its center, extending practically from the bottom to the top edges of the said body, as is clearly shown in Fig. 2.

The supporting-section a' of the supporter consists of a strip of spring material, metal, or other substance of suitable description and of such length that when the two members of the supporter are assembled the ends of the supporting-strip a' may enter the pockets 10 of the body-strip, the central portion of the supporting-strip a' being located between the loop 11 and the body-strip, as is shown in Figs. 1, 2, and 3.

The waistband of the skirt C is provided with a hook 12 near each of its ends at the upper edge and said hooks 12 may be of the ordinary or of any desired formation. After the band of the skirt has been closed or the skirt has been fitted otherwise to the waist B the hooks 12 are made to engage with the upper edge of the supporting member a' of the supporter, and such connection will effectually serve to hold the waistband and the skirt in proper position relative to the waist.

It will be observed that the hooks 12 engage with the supporting-section a' of the supporter at each side of its center, so that the weight of the skirt is distributed along the said supporting-section, and consequently there is little liability of the skirt shifting from its proper position.

It is obvious that when the supporting member a' is removed from connection with the body member a the body member will present no obstacles to the proper washing of the waist and will be in no wise injured by

such treatment. It is furthermore obvious, for example, that after a shirt-waist having the supporter applied has been prepared for wearing, the supporting-section may be quickly and conveniently introduced into the body-section of the supporter, and, further, that ordinary hooks will be all that is required to effect a supporting engagement between the skirt and the supporting device.

Having thus described my invention, I claim as new and desire to secure by Letters Patent—

A garment-supporter, comprising a body-section and a supporting-section, the body-
15 section consisting of a strip of flexible mate-

rial having at each end a pocket and a transverse loop secured to the strip intermediate the pockets, and the supporting-section consisting of a strip of spring material, the ends of which are respectively secured in the pockets of the body-section, and the middle portion of which is inclosed by the said loop of the body-section, whereby to hold the supporting-section and permit the engagement of two hooks therewith, the hooks to be engaged one on each side of the transverse loop.

CHARLOTTE ELIZABETH HURD.
